AIR PURIFYING VENTILATOR FOR TOILET BOWLS

Macy O. Teeter, Newcastle, Ind.

Application May 28, 1934, Serial No. 727,967

17 Claims. (Cl. 4—213)

This invention relates to air purifying ventilators for toilet bowls adapted to withdraw air from the bowl and purify it and deliver the purified air to the room in which the bowl is located.

One of the objects of this invention is to provide an improved structure of the foregoing character which is simple in construction, is inexpensive to manufacture, is easy to install, is highly efficient in operation, and which operates with substantially uniform ventilating and purifying efficiency for practically the life of the structure.

Another object is to provide an improved air purifying ventilator embodying ozonizing means for treating the air withdrawn from the toilet bowl.

A further object is to provide a unitary structure of the foregoing character which is of compact form and neat in appearance; which is adapted for ready application to a toilet bowl; and which includes but few parts, all of which are readily and easily accessible and detachable for inspection, repair and replacement purposes.

A more specific object is to provide a ventilator having a housing rigidly secured to the toilet bowl, the housing being formed of a plurality of separable sections, one of which communicates with the interior of the toilet bowl and contains ozonizing means and another of which contains suction means and serves as a support for the ozonizing and suction means whereby the latter section and ozonizing and suction means may be separated as a unit without disturbing the connection between the housing and toilet bowl.

Other objects and advantages will become apparent as this description progresses and by reference to the drawings wherein,—

Figure 1 is a perspective view of a standard toilet bowl and my improved deodorizing unit attached thereto;

Fig. 2 is a transverse section taken through the lower portion of the unit as on the line 2—2 of Fig. 5;

Fig. 3 is a top plan view of the deodorizing unit attached to the rear portion of the bowl and showing the positioning of the suction nozzle with respect to the bowl, part of the nozzle being shown in section;

Fig. 4 is a cross section on the line 4—4 of Fig. 5 illustrating the manner of attachment of the support to the lower section of the housing;

Fig. 5 is a vertical section through the deodorizing unit with the operating mechanism therein shown in elevation, the same being taken substantially on line 5—5 of Fig. 3;

Fig. 6 is a section on the line 6—6 of Fig. 5 showing the mercury switch and the actuator therefor; and

Fig. 7 is a diagrammatic view of the electrical circuit.

In the drawings, I have shown my invention applied to a toilet bowl 10 having a seat 11 hingedly connected thereto at the rear by a pintle 12. The pintle 12 is provided with supporting posts 14 that pass through suitable openings in the upper rear wall of the bowl and are secured thereto by nuts 15. While I have shown a particular form of bowl and seat structure, it will be understood that my invention is not limited thereto and it has utility in connection with various forms of structures of this general type.

The ventilator, or deodorizer, takes the form of a self-contained unit that may be readily and easily attached to the toilet bowl 10 without the use of separate fastening elements and without modifying or in any way impairing the toilet structure. Specifically, the ventilator or deodorizer shown in the drawings (Figs. 1 and 3) includes a housing 16 having an integral bracket arm 17 extending laterally and rearwardly therefrom to overlie the rear portion of the bowl 10 that carries the pintle posts 14. The arm 17 is provided with openings 18 through which the pintle posts 14 pass so that the ventilating and deodorizing unit is secured in place solely by the toilet seat mounting.

The housing 16 of the deodorizing unit is formed of upper and lower sections 19 and 20 that are detachably secured together (Figs. 4 and 5) in a manner that will be described hereinafter. The lower housing section 20 is provided with circumferentially spaced posts or bosses 21 formed integrally with the upper part thereof. These posts are provided with openings 22 that extend entirely through the lower section 20 and posts 21. Long threaded bolts 23 are passed through the openings 22 and screw threaded into openings 24 in an inwardly extending flange 25 at the lower end of the upper housing section 19. The posts 21 of the lower section define circumferential openings 26 which are covered by a screen 27 securely retained within grooves 28 and 29 provided in the upper and lower sections, respectively, of the housing.

The upper section 19 of the housing has a laterally-extending nozzle 30 integral with the top portion thereof and provided with a passageway 31 communicating with the interior of the housing and the toilet bowl 10 by means of a chambered passageway 31. The nozzle 30 is gen-

- erally flat and is of such size and shape (Figs. 3 and 5) that it may be closely interposed between the top of the bowl 10 and the seat 11 at one side and near the rear, with the open end of the 5 nozzle following generally the contour of the bowl portion over which it is positioned.
- The top portion or head 32 of the upper housing section 19 is convexly shaped, and the interior of this housing section, adjacent said convex head 10, is provided with a partition wall 33 that defines a chamber 34 in the top of the housing for the entrapment of gases withdrawn through the nozzle 30 from the toilet bowl 10. The inner end of the nozzle passage 31 leads directly into 15 the chamber 34. The partition wall 33 has a central opening 35 surrounded by a raised rounded bead 36, thus providing a communication between the chamber 34 and the lower interior portion of the housing 16. The opening 35 is of a 20 size adapted to restrict the flow of the trapped gases from chamber 34 directly downwardly into the lower portion of the housing 16 where it is treated by ozonizing means to be described. The trap chamber 34 and raised bead 36 additionally 25 serve to prevent any water that may be drawn in through the nozzle 30 from finding its way downwardly through the interior of the housing where it may come into contact with the operating elements therein.
- 30 An ozonizer 37, which may take any suitable form, is mounted within the upper housing section 19 directly beneath the opening 35 leading from the trap chamber 34. The ozonizer is supported, preferably, in the following manner: An 35 intermediate supporting member 38 of disk-like form is secured to the lower housing section 20 by threaded bolts 39 (Fig. 4). The support member 38 is provided with openings 40 through which the threaded bolts 23 are adapted to pass for 40 securing of the latter to the upper housing section 19. A suitable ring-shaped gasket 41 is interposed between the upper housing section 19 and the member 38, the central portion of the member 38 being provided with an opening 42 45 providing communication between the two housing sections 19 and 20. The support member 38 is provided with upstanding posts 43 to which a transformer 44 is securely fastened by means of bolts 45. The ozonizer 37 is mounted on the 50 top of the transformer 44, being secured thereto by bolts 46 secured to webs or plates on the top of the transformer (Fig. 5).
- The bottom portion of the lower housing section 20 has an electric motor 47 mounted therein. 55 This motor drives a suction fan 48, preferably, of the "Sirocco" type. The fan 48 is provided with a horizontally-disposed circular disk 49 attached to the motor shaft 50 by a set screw 51. Radially disposed on the disk 49 and extending beyond the 60 edge thereof are a plurality of upstanding fan vanes 52 that, in the operation of the fan, operate to create a suction and withdraw the gases from the toilet bowl 10 through the housing nozzle 30, as will be well understood from the drawings 65 and the foregoing description. The vanes 52 are positioned on the fan disk 49 slightly and radially outward of a depending annular flange 53 around the periphery of the opening 42 in the support member 38.
- 70 The electrical circuit for operation of the motor 47 and ozonizer 37 is controlled by a mercury switch 54 mounted in the bottom portion of the lower housing section 20. The switch 54 is mounted on one end of a support member 55 75 that is pivotally carried near its other end by the

wall of the housing section 20. In this manner the switch support 55, due to the weight of the switch 54, tends to assume a position in which the switch 54 is opened.

The switch 54 is, preferably, moved to its circuit-closing position as follows: The upper housing section 19 is provided with a longitudinal bore 57 in which is mounted a plunger 58. The upper end of the plunger 58 is provided with a laterally extending and rubber-covered arm 59 that projects into a recess or depression 60 in the upper surface of the nozzle 30 whereby turning movement of the plunger 58 is prevented. As will be seen from Figs. 1 to 5, the plunger arm 59 projects beneath and is engaged by the toilet seat 11 in such a way that movement of the seat 11 down upon the bowl depresses the plunger 58. The lower end of the plunger 58 terminates short of the lower end of the housing bore 57, and a reduced diameter rod 60 is secured to the lower end 10 of the plunger. The rod 60 projects downwardly into the lower housing section 20 where its lower end seats in a notch or groove 62 in the switch support 55 whereby depression of the plunger 58 15 rocks the support 55 to close the switch 54. A 20 spring 63 is confined in the housing bore 57, between the lower end of the plunger 58 and the intermediate support member 38, constantly urging the plunger 58 upwardly so that the plunger 25 is raised and the switch 54 opened as the toilet 30 seat is raised.

The ozonizer 37, transformer 44, motor 47 and switch 54 are preferably arranged in the electrical circuit in the manner illustrated in the diagram of Fig. 7. The ozonizer includes an insulating tube 64 (Figs. 5 and 7), about the outer 35 face of which is a tubular electrode 65 that is grounded as at 66. An electrode 67 is mounted on the inner face of the tube and this electrode is connected to one of the secondary terminals 40 68 of the transformer 44. The other secondary terminal 69 is grounded at 70, while the primary 71 of the transformer is connected in circuit from the source of current supply 72 with one of the terminals 73 of the motor 47. The mercury 45 switch 54 and the other terminal 74 of the motor are connected with the returning wire 75 of the circuit.

The operation and advantages of my invention will be obvious from the foregoing description. 50 Upon the depression of the toilet seat 11, the plunger 58 is moved downwardly against the tension of the spring 63 to rock the mercury switch support 55 thereby closing the mercury switch 54 and the electrical circuit operating the ozonizer 55 37 and motor 47. The motor rotates the fan 48 and the foul gases are withdrawn from the bowl 10 through the nozzle 30 into the housing chamber 34, down through the opening 35, through and around the ozonizer 37, and thence through the 60 opening 42 into the lower housing section from which they are expelled through the screened openings 26 into the room atmosphere. In this manner obnoxious gases from the bowl are ozonized and are returned to the room in which the 65 bowl 10 is located in a deodorized and purified condition.

It will be manifest from the foregoing description that my invention is admirably adapted to perform the objects first stated therein. The 70 structure is simple, it is cheap to manufacture, it is attractive and compact in design, it is efficient in operation, and the parts are subjected to a minimum of wear. The ozonizer 37 and transformer 44, while being located within the upper 75

housing section 19, are carried by the lower housing section in such a way that they may be removed as a unit with the lower section, motor 41 and fan 42. This provides an arrangement 5 wherein the parts may be readily and easily inspected, assembled and disassembled, and repaired and replaced.

It will be understood that while only one form 10 of structure embodying the invention has been illustrated and described, various changes in details and arrangements of parts may be made without departing from the spirit and scope of the invention as defined by the claims that follow.

15 I claim:

1. In a ventilator unit for attachment to a toilet bowl, a housing having a supporting arm therefor, said housing having an intake portion integral therewith and positioned adjacent the top 20 of and in communication with the interior of said bowl, said housing extending downwardly from its intake portion and having an exhaust opening extending around the circumference thereof intermediate its ends for permitting communication 25 with the outside atmosphere, and means within said housing for withdrawing air from said bowl and feeding it through said exhaust opening in a purified state.

2. In a ventilator unit for a toilet bowl, a 30 housing, an arm on said housing extending horizontally thereof and secured to the rear portion of said toilet bowl, said housing having an intake nozzle in communication with the bowl, electrically controlled suction and purifying means in 35 said housing, a switch for cutting in and out said suction and purifying means, and a plunger projecting through the housing and intake nozzle and actuated by a bowl-mounted toilet seat for operating said ventilator.

40 3. In a structure of the class described, a housing and a fastening arm therefor, a separate intake portion on said housing interposed between the toilet seat and bowl, an ozonizer and suction device within said housing, means for operating said ozonizer and suction device, and an actuator mounted within said housing and projecting from the top thereof for operation by the toilet seat for cutting in and out said ozonizer and suction device operating means.

50 4. A toilet ventilator unit comprising a housing and an arm therefor, said arm being secured to the rear portion of a toilet bowl and positioning said housing laterally and forwardly from said rear portion with the intake portion of said housing interposed between the seat and bowl and at one side thereof, said housing supporting therewithin an ozonizer and suction device, and means operated by the toilet seat for actuating said ozonizer and suction device for withdrawing obnoxious gases from the bowl and passing them 55 downwardly into and through said ozonizer and through said housing and expelling them to the outside atmosphere in a purified form.

5. In a ventilator attachment for toilet bowls, 60 a housing positioned vertically and laterally of said bowl, an ozonizer and suction means in electrical circuit within said housing, a switch for opening and closing said circuit, a vertically mounted plunger within said housing and operated by a toilet seat for closing the circuit to operate said ozonizer and suction device.

6. A structure of the class described, comprising a housing formed of a plurality of separable sections forming separate compartments, an ozonizer within one of said compartments, suction

fan means and switch means within said housing supported within the other of said compartments, and a plunger within said housing for actuating said switch to operate said ozonizer and suction device.

7. A ventilator attachment for a toilet bowl comprising a housing and an arm formed integrally therewith for attachment to the toilet bowl, a separate intake portion for said housing interposed between the toilet seat and the top 10 of the bowl and in communication with the bowl interior, an ozonizer, suction fan means, and a mercury switch mounted within said housing, a vertically mounted plunger within said housing in engagement with said switch and projecting from said housing for contact with the underside of the toilet seat, the movement of said seat toward the bowl effecting movement of said plunger to actuate said switch to open and close the circuit to operate the ozonizer and fan means. 15

8. In a structure of the class described, a housing formed of a plurality of detachable sections, an ozonizer within one of said sections, suction means within another of said sections, a nozzle on said one section communicating with the interior of said housing and the toilet bowl, a switch in said other section and in circuit with said ozonizer and suction means, a plunger supported by said one section and extending into said other section to actuate said switch for operating said ozonizer and fan means, said plunger also projecting beyond said nozzle for depressible engagement. 20

9. In a structure of the class described, a housing having a suction nozzle adapted to be fixedly 25 attached to and communicate with the interior of the toilet bowl, an upper section forming an upper compartment, a detachable lower section forming a lower compartment, air purifying means supported by said lower section and disposed in said upper compartment, a suction fan and electric motor and motor switch in said lower compartment, and means adapted to be actuated by the toilet seat for opening and closing said switch. 30

10. In structure of the class described, a housing having an upper section forming an upper compartment, a lower section forming a lower compartment, an intermediate section, air purifying means carried by said intermediate section and disposed within said upper compartment, a suction fan carried within said lower compartment, means detachably securing together said upper and lower sections with said intermediate section confined therebetween, and additional means for securing together said lower and intermediate sections whereby said lower and intermediate sections, said air purifying means and said fan may be detached as a unit upon detachment of said first named securing means. 45

11. In structure of the class described, a housing having an upper section forming an upper compartment, means communicating said upper compartment with the interior of the toilet bowl, a lower housing section forming a lower compartment, air purifying means in one of said compartments, suction means in the other of said compartment, means for actuating said suction means and so positioned that said suction means is positioned between it and said air purifying means, said lower section having air discharge 50 openings located laterally of and adjacent said suction means. 60

12. In a ventilator attachment for toilet bowls, a housing adapted to be mounted vertically and having a nozzle portion at the top thereof adapted 75

to be secured to the toilet bowl, said housing including an upper section forming an upper compartment, a lower section detachably connected to said upper section, and forming a lower compartment, said lower section having a lateral passage therein adjacent said upper section, and screen means secured by said upper and lower sections and covering said passage.

13. In a ventilator attachment for toilet bowls, 10 a housing adapted to be mounted in vertical position and having a nozzle portion at its top adapted to be attached to a toilet bowl, said housing including an upper shell-like section having an open bottom, a lower shell-like section having an 15 open top and a closed bottom, spaced upstanding members around the top edge of said lower section adapted for connection to the lower edge of said upper section and providing a plurality of intermediate lateral openings, means for securing 20 said upper and lower shell-like sections together, a screen covering said openings and interlockingly engaged with said upper and lower sections.

14. In structure of the class described, a housing 25 adapted to be mounted in vertical position and having a nozzle portion at its top adapted to be attached to a toilet bowl, said housing including an upper shell-like section having an open bottom, a lower shell-like section having an open 30 top and a closed bottom, spaced upstanding members around the top edge of said lower section adapted for connection to the lower edge of said upper section and providing a plurality of intermediate lateral openings, means for securing 35 said shell sections and upstanding members together, a screen covering said openings and interlockingly engaged with the upper and lower sections, an air purifying means, an electric motor and an intermediate suction means carried by said lower section with said air purifying means located in said upper section and said suc-

tion means located to discharge purified air through said openings intermediate said air purifying means and said motor.

15. In structure of the class described, a housing 10 which includes an upper section having a main chamber and a trap chamber connecting with said main chamber through a narrow passageway, conduit means connecting said trap chamber with the toilet bowl, said housing also including a lower section, air purifying means located in said main chamber in the direct path of air flowing through said narrow passageway, suction means in said lower section, means adjacent said suction means for discharging air, and means for operating said suction means. 15

16. In a deodorizing attachment for toilet bowls including a seat, a housing having a nozzle formed integrally therewith and projecting laterally from the top thereof, suction means and ozonizing means within said housing, a plunger 20 reciprocably mounted within said housing and projecting from the top thereof, a switch controlling operation of said ozonizing and suction means, and an arm on said plunger adapted to be engaged by the seat for depressing said plunger 25 to actuate said switch.

17. In a deodorizing attachment for toilet bowls, including a housing having a nozzle formed integrally therewith and projecting laterally from the top thereof, a depression formed in 30 the top of said nozzle, suction means and ozonizing means within said housing, a plunger mounted within said housing and projecting outwardly therefrom, the top of said plunger being confined within said depression and adapted to be 35 actuated by the movement of the toilet seat, and a switch actuated by depression of said plunger to set said ozonizing and suction means in operation.

MACY O. TEETOR. 40
